UNITED STATES PATENT OFFICE.

GEORGE H. LUTZ, OF DAHLONEGA, GEORGIA.

DIPPER-DREDGE.

1,088,031.

Specification of Letters Patent.

Patented Feb. 24, 1914.

Application filed October 30, 1912. Serial No. 728,715.

To all whom it may concern:

Be it known that I, GEORGE H. LUTZ, a citizen of the United States, and a resident of Dahlonega, in the county of Lumpkin 5 and State of Georgia, have invented certain new and useful Improvements in Dipper-Dredges, of which the following is a specification.

This invention relates to dredges operating upon the principle of a scoop or dipper for raising material, and particularly to such dredges as are used for raising material from the bed of a body of water.

It is customary to provide dredging dippers with movable bottoms or rear ends which can be opened when the dipper reaches the dumping point for the purpose of discharging the contents. But it is difficult to effect a tight closure of dippers of this 20 class, even by the use of expensive packings or gaskets, and impracticable to maintain tight closures without repeated renewal of the packings. The result is that there is more or less leakage in the operation of the 25 dredge and when used in working gold bearing deposits, the finely divided values largely escape with the leakage.

The object of the present invention is to provide an absolutely tight dredging dipper 30 and means for conveniently operating the same, both for gathering and discharging the material.

In carrying out the invention, the dipper is made with its side and end walls permanently and hermetically united so that it will 35 hold all material which may enter it, up to its full capacity, without leakage; and to provide for dumping, the dipper is mounted and equipped to be rotated upon an axis.

The invention will be fully understood 40 upon reference to the accompanying drawing, in which,

Figure 1 is a general view of a dredge in which my improvements are embodied; and 45 Fig. 2 is a detailed view of the dipper, and a portion of its mounting.

1 represents the dipper which has its rear end wall 2 permanently and hermetically united with its side walls 3 so that when 50 the dipper is elevated, the contents will not leak out. If the dipper is to be operated in a more or less vertical position, as suggested in Fig. 1, it will also have a forward wall, which will likewise be hermetically united 55 with the side walls 3 and be suitably constructed to gather the material by scooping

action. The dipper 1 is conveniently mounted upon a beam 5 for the purpose of directing its movements and is suitably connected with the operating cable 6 for imparting the 60 scooping and elevating movements to the dipper. In order that the dipper may be delivered of its contents, after it has been raised and swung to the dumping position, it is mounted to rotate upon an axis, preferably 65 extending longitudinally of the dipper. This is conveniently accomplished by providing the dipper with a rotating shank 7 mounted in bearings 8 upon the beam 5, and in order that the necessary rotation for 70 dumping may be imparted to the dipper at will, it is provided with rotating means, such for instance as the gear wheel 9 on the shank 7 and the driving pinion 10. The latter may be conveniently driven through the 75 means of a shaft 11, extending from any suitable source of power, such for instance as the prime mover 12 in the form of an electric motor. In the illustrative embodiment, the motor 12 is mounted on the beam 80 5 and drives the shaft 11 through the medium of the gearing 13. To avoid interfering with the rotation of the dipper 1 by the driving connection 6, the dipper is supported by said driving connection, through the medium of the endless belt 14, preferably in the form of a chain, passing through the pulley 15 and around the dipper 1, so that the dipper may freely turn when desired. To 85 confine the chain against displacement upon the dipper, when the draft is more or less in the direction of the axis of the dipper, the dipper is equipped with curbing 16, conveniently provided from angle-iron.

With the dipper constructed and operated 90 as above described, the fine material, in which the values mainly lie in gold dredging, for instance, is entirely saved.

I claim:

1. In a dredge, a dipper having hermetically united confining walls, a rotary mounting for said dipper comprising a non revoluble oscillating beam, an operating connection for oscillating said beam with the dipper and a sling through which the operating connection supports the dipper and which permits rotation of the dipper relatively to said operating connection, said rotary mounting being carried on one side of said beam, said operating connection having a pulley around which said sling passes, and said dipper having an external curb 100 105 110

against which said sling rests, said curb being bent back to permit the bending of said sling in the plane of oscillation of said beam.

- 5 2. In a dredge, a dipper having hermetically connected confining walls, a non-revoluble oscillating carrier, a rotary mounting for said dipper seated on said carrier, an operating connection for the dipper, supporting means through which the operating connection supports the dipper and which means permits rotation of the dipper relatively to said operating connection, said

means comprising an endless belt surrounding the dipper, a pulley for said belt on said operating connection, and a confining curb for said belt on said dipper permitting the bend of said belt in the vertical plane of said carrier.

The foregoing specification signed at 20 Dahlonega Ga. this tenth day of August, 1912.

GEORGE H. LUTZ.
